assignors to Greene Manufacturing Co., Inc.,
Racine, Wis., a corporation of Wisconsin

Application December 11, 1948, Serial No. 150,102

Term of patent 14 years

(Cl. D85—2)

To all whom it may concern:

Be it known that we, Carl P. Albert and Ewalt H. Rocks, citizens of the United States, residing at Racine, in the county of Racine, and State of Wisconsin, have invented a new, original, and ornamental Design for a Smoking Stand, of which the following is a specification, reference being had to the accompanying drawing, forming a part thereof, in which,

Fig. 1 is an elevational view of a smoking stand, showing our new design;

Fig. 2 is a top view thereof;

Fig. 3 is an enlarged detailed sectional view taken along line 3—3 of Fig. 2; and

Fig. 4 is a section taken along line 4—4 of Fig. 1.

Both side elevations and the rear elevation are identical to the elevation of Fig. 1.

We claim:

The ornamental design for a smoking stand, as shown and described.

CARL P. ALBERT.
EWALT H. ROCKS.
